US00D337100S

United States Patent [19]
Iino

[11] **Patent Number:** Des. 337,100
[45] **Date of Patent:** ** Jul. 6, 1993

[54] **ELECTRONIC COMPUTER**

[75] Inventor: Masaaki Iino, Yokohama, Japan
[73] Assignee: Kabushika Kaisha Toshiba,
Kanagawa, Japan
[**] Term: 14 Years
[21] Appl. No.: 870,091
[22] Filed: Apr. 15, 1992
